AUTOMATIC STOP AND REPEATING MEANS FOR GRAPHOPHONES.

1,406,607.

Specification of Letters Patent. Patented Feb. 14, 1922.

Application filed September 14, 1917. Serial No. 191,395.

To all whom it may concern:

Be it known that we, CLIFFORD C. BROOKS and EDWIN O. KLEMM, citizens of the United States, residing at Saginaw, in the county 5 of Saginaw and State of Michigan, have invented certain new and useful Improvements in Automatic Stop and Repeating Means for Graphophones, of which the following is a specification.

- 10 The improvements of this invention have to do with sound reproducing machines and embody certain novel repeating and stopping control devices. The repeating means employed is of a type heretofore proposed 15 by us and comprising certain actuating means operable from the driving motor of the sound producing machine and timed in its action to cause a slight elevation of the reproducing stylus when the latter reaches 20 the reproduction discontinuance point, thereafter carrying the reproducer to its predetermined reproduction commencement point respecting the record and depositing 25 said reproducer upon the record for the sound reproduction operation. The actuating means for the reproducer above referred to is of utility for effecting a single reproduction of a record, or repeated reproductions as may be controlled by a suitable 30 operation predetermining device associated with said actuating means.

The essential novelty of the present invention resides in the simplified actuating instrumentalities for the reproducer whereby 35 these instrumentalities are considerably reduced in number, and may be made largely of metal stampings conducive to cheapness and wearing qualities, and generally afford a desirable arrangement of mechanical parts.

40 Our present improvements also involve a novel form of reproduction commencement point controlling device associated in a peculiar way with the actuating instrumentalities for shifting the reproducer to its 45 starting point in relation to the record, together with certain other detail features of construction which will be fully set forth in the aftergoing description, and illustrated in the accompanying drawings, in 50 which—

Figure 1 is a fragmentary plan view of the base portion of the cabinet of a sound reproducing machine showing the record table or platform with a record thereof, and 55 these parts broken away to make clear the

arrangement of the parts of the reproducing actuating means. In this figure the tone arm is shown in section and dotted lines indicate the position of the reproducer when disposed in its predetermining stopping position, from which position it is mechanically shifted to its reproduction commencement point position.

Figure 2 is a view similar to Figure 1 excepting that the reproducer is shown as 60 when carried outwards to its reproduction commencement point position, a typical form of operation predetermining and stopping device being also illustrated.

Figure 3 is a view similar to Figure 2 70 except that the reproducer is shown released from the actuating means by which it is being carried outwards as shown in Figure 2, said reproducer as illustrated being in the act of traversing the record toward the 75 inner limit of its travel.

Figure 4 is a sectional view on the line 4—4 of Figure 1.

Figure 5 is a sectional view approximately on the line 5—5 of Figure 2.

Describing the invention specifically. A denotes the base of the sound reproducing machine cabinet, the latter being equipped with the customary motor driven record carrier B which is a rotative table or platform illustrated in the drawings as actually carrying the record C. The reproducing machine is equipped with the customary tone arm which as seen in Figure 4 has a sort of ball and socket connection established by 90 the elements 2 and 3, with the base A, such connection permitting of raising and horizontal swinging movements of the tone arm 1. The tone arm 1 is supplied with the usual sound box 4 having the reproducing stylus 5 and for the purposes of this description the parts 1, 4 and 5 will be termed reproducing means or a reproducer, the same coacting with the record C in the customary manner.

As seen in Figures 4 and 5 the record carrier B is supported by a spindle 9 of customary form, the latter being driven from the motor of the machine, not shown. Adjacent to the spindle 9 is a driver in the 105 form of a shaft 6 carrying a lug wheel 7 provided with upstanding lugs 8 and this driver is preferably connected with the spindle 9 by gearing or any similar connection, not shown, or the driver might be 110

actuated by some other means, this being immaterial to the invention.

The means for shifting the reproducer over the record C for the starting of reproduction action thereof, or for effecting repeated reproductions, is operated from the driver including the parts 6, 7 and 8. The actuating means comprises a shifting lever 10 pivoted at 11 to a stud 12, see Figure 4, said stud 12 being itself rotatively mounted in the base A. At its outer end the lever 10 projects from beneath the record carrier B and is formed with a bifurcated portion 10^a receiving therein the lower reduced extremity of an L-shaped arm 13 which is fixed to the tone arm 1 near the supporting connection for the latter. At its inner or opposite end the lever 10 is formed with a rise or cam 10^b and this end portion is curved slightly toward the axis of the actuating lever 14 which cooperates with said shifting lever. The actuating lever 14 is pivoted on the base A at 15, and said lever comprises a main body portion of somewhat bell crank form including an outwardly projecting arm 16, and an auxiliary arm 17. The auxiliary arm 17 as shown in Figure 4 is practically a separate plate secured at 18 to the axial portion of the lever 14, and said arm 17 overlaps the lever 10 and is adapted on pivotal movement of the lever 14 to ride up and on the cam 10^b of the lever 10. The cooperation between the arm 17 and the lever 10 is such that rocking of the lever 14 will engage the arm 17 with the cam 10^b and rock the inner end of the shifting lever 10 downwards, thereby elevating its outer end and raising the reproducer slightly to disengage the stylus 5 from the record C.

In the practical operation of the present invention it is contemplated to predetermine the point at which the reproducer will discontinue reproduction, in the length of the record C, by the mere act of depositing the stylus 5 upon the record at any point desired. When so deposited the actuating and controlling instrumentalities hereinbefore and hereinafter to be set forth will operate in such a way as to effectuate the mechanical shifting of the reproducer from such reproduction discontinuance point to a reproduction commencement point and after the desired reproduction, once or more times, said reproducer will stop automatically at the predetermined discontinuance point. With the above in mind it is obvious that in addition to the raising of the reproducer from the record C, in the manner before described, through the tilting of the lever 10 about its horizontal axis it is necessary to turn the lever 10 upon its vertical axis, which is the stud 12. For this purpose there is mounted on the stud 12 the arm 19, movement of which is adapted to cause ro-

tation of the pivot stud 12 and the lever 10 fixed to rotate therewith. The arm 19 as seen in Figures 1 to 3 inclusive is disposed in the path of movement of a projection 20 extending upwards from a plate 21 supported on the outer arm 16 of the lever 14. The plate 21 has a pin and slot pivot connection at 22 with said arm 16 and mounted on the arm 16 is an eccentrically pivoted disk 23 the pivot 24 of which is shown in Figure 1, said pivot also being provided with a knob or handle 25 by which the disk is readily turned. By turning the disk 23, and owing to the engagement of this disk within a ring 26 forming an extension of the plate 21, it will be evident that the projection 20 cooperative with the arm 19 is capable of being moved relatively to said arm in various adjusted positions.

To establish a driving connection between the driver or shaft 6 and the lever 14 a link 27 is provided, said link being connected at one end with the inner arm of the lever 14 and being formed with a flange lug 27^a at its other end, the lug 27^a adapted to engage the lugs 8 of the lug wheel 7. If the record carrier B is released from the detaining action of the brake shoe 28, see Figure 2, said carrier will start to rotate in the customary way and as a result an adjacent one of the lugs 8 of the driving lug wheel 7 will engage the flange lug 27^a of the link 27. In this manner the link 27 is pulled upon to rock the lever 14 and the initial rocking of said lever 14 moves the arm 17 and rocks the shifting lever 10 about its horizontal axis. In this way the reproducer is raised in respect to the record disengaging the stylus 5 from the latter. The rocking of the lever 14 at a certain time brings the lug 20 of the plate 21 into engagement with the arm 19 and on such engagement the arm 19 is moved inwards a predetermined extent dependent upon the adjustment of the plate 21.

As a result of the actuation of the arm 19 the shifting lever 10 is turned with the stud 12 as a vertical axis, thereby causing the reproducer to be moved toward the outermost groove of the record C to its reproduction commencement point upon said record. The extent of this outward movement of the reproducer by the coaction of the parts 21 and 19 depends upon the adjustment of the plate 21. The adjustment of the plate as in Figure 1 is such as to carry the reproducer to the outermost reproducing portion of a typical twelve inch record C, this condition being indicated by indicia on the parts 23 and 26 which indicia comprises numerals denoting the different sizes of records and an arrow on the disk 23 adapted to be adjusted opposite the numerals or at intermediate points as may be desired.

It will be apparent that if the eccentric disk 23 is turned to shift the lug 20 of the plate 21 away from the arm 19, according to the arrangement of the parts as seen in Figure 1, on subsequent actuation of the lever 14 the lug 20 will engage the arm 19 some time after the lever 14 begins to move, and under these conditions the shifting lever 10 will not be moved as great a distance as is required according to the adjustment in Figure 1. It is in this way, namely, by adjusting the lug 20 with the plate 21 to positions at various distances from the arm 19, that admits of shifting the arm 19 a greater or less distance, and consequently the lever 10 and the connected reproducer, whereby variable shifting actions of the reproducer may be obtained to cause it to be deposited upon records of different sizes at proper reproduction points, or deposited upon a record of a certain size at any desired point in the length of said record.

The manner in which the reproducer is shifted to its reproduction commencement point on the record having been set forth, reference will now be made to the means for stopping the reproducer automatically when it reaches its predetermined, and likewise variable, reproduction discontinuance point. For this purpose a timing or operation control member is employed and is shown at 29, said member being mounted upon the pivot stud 12 and frictionally connected with the stud by means of tension and lock nuts 30 and 31 respectively, which are screwed upon the threaded portion of the stud 12. The timing member 29 is formed with a lateral extension 29^a provided with a notch 29^b. The notch 29^b is adapted to receive therein a lug 14^a stamped out of the arm 16 of the lever 14. Under normal conditions, that is, when the record carrier B is stationary, the lug 14^a is engaged in the notch 29^b of the member 29. Therefore it is possible to move the reproducer arm 1 back and forth over the record to set the stylus 5 at any point in the length of the record as a predetermined stoppage point for reproduction and during such operation the timing member 29 is stationary. The positive interlocking connection between said member and the lever arm 16 prevents the timing member from moving with the lever 10 and arm 19 which of course must move during the manipulation of the tone arm 1 in setting the reproducer preliminarily to the said reproduction discontinuance point.

When, however, the record carrier B is released and the driver 6 starts to rotate along with the carrier owing to such release, the first action of the driver through the link 27 is to tilt the lever 14 to disengage the lug 14^a from the notch 29^b of the timing or trip member 29. In this way the member 29 is freed on the initial movement of the record

carrier so that when the lever 14 has moved enough to raise the reproducer from the record, as soon as the outward swinging movement of the reproducer starts, compelled by the shifting lever 10 the frictional connection between the timing member 29 and the part 19 comes into play to cause the member 29 to move with the lever 10 in the same direction as the part 19, namely inwards or towards the axis of the record. 70 75

At a certain time in the turning movement of the lug wheel 7 of the driver 6 a spring 32 connected at one end with the pivot which connects the parts 14 and 27 and passing at its other end through an eye 33 on the link 27 comes into play to position the link 27 relatively to the lever 14 whereby disengagement between the flange lug 27^a and the cooperating lug 8 is effected. At the time of this disengagement the notch 29^b of the member 29 is no longer opposite the lug 14^a of the lever 14. On such disengagement of the parts 27^a and 8 a spring 34 connected with the lever 14 pulls the lever 14 in a direction toward resuming its normal position. 80 85 90

Such movement is limited, however, by engagement of the lug 14^a with the inner edge of the extension 29^a of the timing member 29. It being recalled that the freeing of the member 29 from the detaining action of the lug 14^a thereafter permits of movement of the member 29 with the stud 12 and therefore synchronously with the reproducer and lever 10, it will be obvious that while the reproducer is traveling toward the discontinuance point on the record C, as depicted in Figure 3, the lever 10 is gradually moving therewith on account of the connection between the parts 13 and 10, and likewise the timing member 29 and the arm 19 are moving gradually outwards owing to their frictional connection with one another and connection with the stud 12 which is actuated by the lever 10. When the member 29 has been moved far enough to cause its notch 29^b 100 105 110 to arrive opposite the lug 14^a owing to the influence of the spring 34 there will be a sudden rocking of the lever 14 to its normal position effecting the normal interlocking of the lug 14^a in said notch. This final 115 return of the parts to normal does one or two things according to the adjustment of an operation predetermining device. One thing is always effected by such action and that is the movement of the link 27 to a 120 125 position wherein its lug 27^a is again in the path of the lugs 8. If the machine is set for a repeated operation the engagement between a lug 8 and the lug 27^a will be compelled, the lever 14 rocked and the reproducer carried outward on the record and deposited at its proper reproduction commencement point according to the cycle of action which has just been fully described. If, on the other hand, the machine is set for 130

the stopping of the reproduction on the return to normal of the lever 14 after one or more cycles of reproduction controlling operations the brake shoe 28 will be automatically applied incident to the reentering of the lug 14^a into the notch 29^b of the timing member 29 so as to engage the record carrier B and stop the sound reproducing operation. Of course the stoppage of the record carrier B stops the driving of the lug wheel 7 and though the lug 27^a is ready to be engaged by a lug 8 it will not be so engaged owing to such stoppage.

The operation predetermining device controlling the stopping or repeating actions of the operating instrumentalities herein set forth includes means heretofore proposed by us comprising a rod 35 connected with an arm 36 fixed to the axis of the lever 14 so as to move with the lever. The rod 35 is connected to a short lever 37, see Figures 2 and 3, loosely mounted on a shaft 38 to which shaft is fixed a disk 39 and a ratchet wheel 40. At its free end the lever 37 has a pawl 41 engaging a wheel 40, and the disk 39 has the notch 39^a adapted to move opposite to a lug 42 upon the brake lever 43 which carries the brake shoe 28. By turning shaft 38 through the provision of a suitable handle or like means so that the notch 39^a no longer receives the lug 42 of the lever 43, said lug will ride on the periphery of the disk 39 and the lever 43 will be held in a position maintaining the brake shoe 28 out of engagement with the record carrier. The connection between the lever 14 and the disk 39 is such that if we assume that the disk 39 has been turned one increment of movement to effect a single reproduction of the record the brake shoe 28 will be released, the record will be reproduced and at the completion of the reproduction the lug 14^a being permitted to enter the notch 29^b causes a final rocking of the lever 14. The final rocking of the lever 14 as previously generally mentioned under the influence of the spring 34 effects a pull upon the rod 35 and turns the disk 39 one increment of movement back to its original position, owing to the ratchet and pawl connections set forth. Such turning of the disk 39 causes the notch 39^a to move opposite the lug 42 and the brake lever 43 is permitted to move slightly to cause reengagement of the brake shoe 28 with the record carrier B, thereby stopping the latter. If the disk 39 is set by more than one increment of movement it will be necessary that there be performed a complete predetermined reproduction of the record for each increment of movement imparted to the disk 39 in its adjustment owing to the fact that it requires a reproduction of the record to shift the disk 39 a single increment of movement toward its normal or stopping position.

The manner in which the member 29 acts to time the sound reproduction operation whether the latter is to be performed a single time or a number of times will be more fully apparent when it is understood that the member 29 is held stationary by the locking means or lug 14^a during all movements of the reproducer which are effected by manipulation. That is, when the operator manually moves the reproducer arm 1 to set the reproducer at the point where reproduction is to stop, the member 29 always maintains the locked position of Figure 1, and this position therefore invariably represents a constant adjustment of the timing member in correspondence with the reproducer predetermining that point to which the timing member must move, for the stopping of reproduction and which point is always fixed no matter where the operator sets the reproducer for predetermining its stopping position. Thus it is that after such setting of the reproducer the mechanical shifting of the same to reproduction commencement position, which is a variable action under the control of the member 21, the extent of movement of the member 29 carrying its notch 29^b away from the lug 14^a is always equal to the extent of movement of the reproducer from its reproduction stopping point position to its reproduction commencing position. For this reason the traverse of the member 29 and reproducing traverse of the reproducer always correspond, enabling the discontinuance of reproduction at the proper time or simultaneously with the arrival of the reproducer at the point of discontinuance of reproduction.

The expressions employed in certain following claims referring to devices connected with the reproducer should be interpreted in the light that the connections are indirect being made through the intervening tone-arm and possibly other parts.

Having thus described the invention, what is claimed as new is:

1. In a sound reproducing machine, the combination with a record carrier and a reproducer adapted to traverse a record thereon, of a part connected to the reproducer to move it to a reproduction commencement point and to be then moved by and with the reproducer during reproduction operation of the latter, an actuating device for said part, a driver for said device, a timing member connected with said first part to move to and from reproduction commencement point therewith, and means intermediate the timing member and actuating device to render the latter operative by the driver at a certain time during movement of the timing device as the reproducer moves from said reproduction commencement point.

2. In a sound reproducing machine, the

- combination with a record carrier, and a reproducer adapted to traverse a record upon the carrier, of means to move the reproducer to a reproduction commencement position, 5 comprising a lever arranged to elevate and swing the reproducer and a single actuating member equipped with an arm to effect vertical movement of the lever, and a second arm having means to cause lateral movement 10 of the lever.
3. In a sound reproducing machine, the combination with a record carrier, and a reproducer adapted to traverse a record upon the carrier, of means to move the reproducer to a reproduction commencement position, comprising a lever arranged to elevate and swing the reproducer, a single actuating member equipped with an arm to effect vertical movement of the lever, a second 15 arm having a part adjustable to cause variable lateral movement of the lever, and means to adjust said part and constructed to control movement of the lever laterally according to different sized records upon the 20 carrier.
4. In a sound reproducing machine, the combination with a record carrier and a reproducer adapted to traverse a record thereon, of a part connected to move with the reproducer to a reproduction commencement point and to be then moved by the reproducer during reproduction operation of the latter, an actuating device for said part, a driver for said device, a timing member connected with said first part to move to and from reproduction commencement point therewith, the 25 connection between the timing member and the said first part admitting of variation of the timing functioning of said member, and means intermediate the timing member and actuating device to render the latter operative by the driver at a certain time during movement of the timing device as the reproducer moves from said reproduction commencement point.
8. In a sound reproducing machine, the 30 combination with a record carrier and a reproducer adapted to traverse a record thereon, of a part connected to move with the reproducer to a reproduction commencement point and to be then moved by the reproducer during reproduction of the latter, an actuating device for said part, a driver for said device, a timing member connected with said first part to move to and from reproduction commencement point therewith, and means intermediate the timing member and actuating device to render the latter operative by the driver at a certain time during movement of the timing device as the reproducer moves from said reproduction commencement point, the last named means interlocking the timing member and the actuating device at a certain time in the movement of the former with the reproducer so as to hold the timing device relatively stationary notwithstanding manual movement of the reproducer with which the timing device is indirectly connected by the first mentioned part.
5. In a sound reproducing machine, the combination with a record carrier, and a reproducer adapted to traverse a record upon the carrier, of means to move the reproducer to a reproduction commencement position, 50 comprising a lever connected at one end with the reproducer and having a cam at its other end, and a single actuating member having a part to engage said cam to shift the lever vertically, and a second part to move the lever laterally.
6. In a sound reproducing machine, the combination with a record carrier and a reproducer adapted to traverse a record thereon, of a part connected to move with the reproducer to a reproduction commencement point and to be then moved by the reproducer during reproduction operation of the latter, an actuating device for said part, a driver for said device, a timing member connected with said first part to move to and 55
- from reproduction commencement point therewith, means intermediate the timing member and actuating device to render the latter operative by the driver at a certain time during movement of the timing device 70 as the reproducer moves from said reproduction commencement point, and stopping means for the reproducer also controlled by the means last above mentioned.
7. In a sound reproducing machine, the 75 combination with a record carrier and a reproducer adapted to traverse a record thereon, of a part connected to move with the reproducer to a reproduction commencement point and to be then moved by the reproducer during reproduction of the latter, an actuating device for said part, a driver for said device, a timing member connected with said first part to move to and from reproduction commencement point therewith, the 80 connection between the timing member and the said first part admitting of variation of the timing functioning of said member, and means intermediate the timing member and actuating device to render the latter operative by the driver at a certain time during movement of the timing device as the reproducer moves from said reproduction commencement point.
8. In a sound reproducing machine, the 85 combination with a record carrier and a reproducer adapted to traverse a record thereon, of a part connected to move with the reproducer to a reproduction commencement point and to be then moved by the reproducer during reproduction of the latter, an actuating device for said part, a driver for said device, a timing member connected with said first part to move to and from reproduction commencement point therewith, and means intermediate the timing member and actuating device to render the latter operative by the driver at a certain time during movement of the timing device as the reproducer moves from said reproduction commencement point.
9. In a sound reproducing machine, the 90 combination with a record carrier, and a reproducer adapted to traverse a record upon the carrier, of means to move the reproducer to a reproduction commencement position, comprising a lever, a connection 95 between the lever and reproducer such that the two may move together, reproduction stop means, a timing member controlling the operation of said stop means movable with the lever, an element locking the timing 100
- 105
- 110
- 115
- 120
- 125
- 130

member against movement with the lever when the latter is moved by the reproducer, and means to release the timing device when the reproducer is being moved by the lever 5 to reproduction commencement position.

10. In a sound reproducing machine, the combination with a record carrier, and a reproducer adapted to traverse a record upon the carrier, of means to move the reproducer to a reproduction commencement position comprising mechanism operable to shift the reproducer and then adapted to be operated by the reproducer as it moves with a record, and reproduction stopping means controlled 15 from said mechanism.

11. In a sound reproducing machine, the combination with a record carrier, and a reproducer adapted to traverse a record upon the carrier, of means to move the reproducer to a reproduction commencement position comprising mechanism operable to shift the reproducer and then adapted to be operated by and with the reproducer as an incident to the reproducing coaction of the reproducer 25 with a record, reproduction stopping means controlled from said mechanism, including a timing member movable with said mechanism, and means to lock the timing member against movement with the reproducer when 30 the latter is manipulated to set it at will relatively to the record.

12. In a sound reproducing machine, the combination with a record carrier, and a reproducer adapted to traverse a record upon the carrier, of means to move the reproducer to a reproduction commencement position comprising mechanism operable to shift the reproducer and then adapted to be operated by and with the reproducer as an incident to 35 the reproducing coaction of the reproducer with a record, reproduction stopping means controlled from said mechanism, including a timing member movable with said mechanism, and means to lock the timing member 40 against movement with the reproducer when the latter is manipulated to set it at will relatively to the record, the last means comprising operating means for the reproducer. 45

13. In a sound reproducing machine, the combination with a record carrier, and a reproducer adapted to traverse a record upon the carrier, of means to move the reproducer to a reproduction commencement position comprising mechanism operable to shift the reproducer and then adapted to be operated by and with the reproducer as an incident to the reproducing coaction of the reproducer 50 with a record, reproduction stopping means controlled from said mechanism, including 55 a timing member movable with said mechanism, and an actuating lever for operating said mechanism in the manner stated and adapted to interlock with the timing member to prevent movement of the latter with 60 said mechanism under certain conditions. 65

14. In a sound reproducing machine, the combination of a record carrier and a reproducer adapted to cooperate with a record upon said carrier, a lever connected with the reproducer to move therewith, an actuating lever comprising the following parts i. e. an arm adapted to engage and tilt said lever in one direction, and a second arm having means to shift said lever in another direction; and a third arm connected to move 70 with the first named lever, automatic means to operate the actuating lever, and means on the actuating lever coacting with the third arm to hold the automatic means inactive a predetermined time. 75

15. In a sound reproducing machine, the combination of a record carrier and a reproducer adapted to cooperate with a record upon said carrier, a lever connected with the reproducer to move therewith, an actuating lever comprising arms, one arm adapted to engage and tilt said lever in one direction, the other an arm having means to shift said lever in another direction, said shifting means embodying a plate pivoted to said 80 second arm and having an engaging lug to act on said first lever, and manipulative means to adjust the position of the plate whereby to arrange said lug at different distances from the portion of the first lever on 85 which the lug acts. 90

16. In a sound reproducing machine, the combination of a record carrier and a reproducer adapted to cooperate with a record upon said carrier, a vertically tiltable and laterally swinging lever connected with the reproducer to raise and swing the same, an actuating lever having an arm engageable with said first lever to tilt the latter vertically and embodying a main arm, an adjustable member upon said main arm cooperative with the swinging lever to shift it laterally, and a timing member also connected with the first lever so that it may move therewith and independently thereof, 100 the actuating lever being provided with locking means for holding the timing member stationary during manipulative setting adjustment of the reproducer, said timing member having means to maintain the locking means aforesaid inactive during reproducing movement of the reproducer, and reproduction stopping means adapted to be operated by the actuating lever as an incident to movement of said lever whereby the 105 locking means aforesaid is caused to move into locking cooperation with the timing member. 110

17. In a sound reproducing machine, the combination of a record carrier and a reproducer adapted to cooperate with a record upon said carrier, an element connected with the reproducer to move therewith, a timing member connected with said element to move therewith and independently thereof, lock- 115 120 125 130

ing means cooperative with the timing member to maintain the latter stationary on certain movement of the reproducer, means for releasing the locking means from the timing member, said timing member comprising a part adapted to hold the locking means inactive during a predetermined amount of movement of the timing member under the influence of the reproducer and to subsequently release the timing member from the locking means.

In testimony whereof we affix our signatures.

CLIFFORD C. BROOKS.
